INVENTOR

Max Vivier
BY Maurice Blandau

ATTORNEY

UNITED STATES PATENT OFFICE

MAX VIVIER, OF NEW YORK, N. Y.

SHADE

Application filed March 8, 1928. Serial No. 259,960.

The present invention relates to shades or screens and the like and has for an object to provide an improved ornamental shade and an improved method of producing certain desired ornamental effects thereon.

4 Shades, screens and the like, such as are used either to serve as a screen to conceal what is behind them, or to moderate the light coming from some bright source, are made ornamental in various ways. The present invention provides an expedient by which screens that are viewed by transmitted light can provide certain light effects to produce attractive contrasts.

10 15 The invention has been developed more particularly in connection with the production of a shade for electric lamps and for convenience of disclosure such an embodiment of the invention will be described, but 20 it will be understood that the description is illustrative merely.

Referring to the drawing—

Figure 1 is a perspective view of a lamp shade designed to be applied, for example, to 25 a double electric wall fixture, and

Figures 2, 3, 4 and 5 are perspective detail views showing the mechanical construction of details of the shade.

30 Fig. 6 is a detail sectional view taken on the line VI—VI of Fig. 1.

The shade shown for the purpose of illustrating the invention comprises a main translucent sheet of parchmentized paper having thereon a suitable design together with a 35 plurality of auxiliary sections secured to said main sheet and cooperating with the design of the main sheet to form a complete design. As shown, the main sheet 5 with the view thereon is embellished by 40 clouds 6, 7, the boat with sails 8 and 9, water lilies 10, 11 and a flying bird 12.

It is a feature of the invention that the 45 ornamentation is afforded in part by means of translucent or transparent auxiliary sections secured to the main translucent sheet in a manner to provide varied light effects. In the arrangement shown, the auxiliary sections are secured to the main sheet at one or more edges and curved away from said main sheet. The several sections cooperate with

the design of the main sheet to form the complete design.

The auxiliary sections of the water lilies shown in the foreground are secured along their lower edges to the main sheet and stand outwardly therefrom. The main sheet is apertured beneath these auxiliary sections and adjacent the upper edge of the flower in such a manner that the light from the electric lamps behind the shade may strike 55 against the under face of the auxiliary section and be reflected in part upwardly against the outer face of the main sheet thus providing a novel light effect.

The sails 8, 9 of the boat shown in the 60 foreground consist of pieces of semi-transparent material which permit the outline of the landscape to be seen therethrough to some extent when the shade is viewed by 65 transmitted light.

The clouds 6, 7 are formed of translucent sections secured at their edges to the main sheet and bowed outwardly therefrom. The main sheet is apertured as indicated at 15 behind the cloud sections to permit the light to 70 shine through and illumine the translucent 75 sections.

The bird 12 shown in flight is shown with a wing consisting of a translucent section 16 secured at its edges and bowed outwardly 80 from the main sheet.

In the several ornamental elements the light shines through the transparent or translucent auxiliary sections in a manner to give 85 life to the design and relieve the flatness of the shade.

The foregoing specific description is illustrative merely and is not intended as defining the limits of the invention.

I claim—

1. A shade of the character described to be viewed by transmitted light comprising a main translucent sheet having a design thereon, a plurality of translucent auxiliary sections secured to said main sheet and having 95 portions bowed outwardly therefrom, said main sheet having apertures behind some of said auxiliary sections to permit direct illumination of parts of said auxiliary sections, some of said auxiliary sections being semi- 100

transparent to permit the outline of the design on the main sheet to be seen through said transparent sections.

2. A shade of the character described to be viewed by transmitted light comprising a main translucent sheet having a design thereon, a translucent auxiliary section secured to said main sheet and extending outwardly therefrom at one edge, the main sheet being 10 apertured behind said auxiliary section toward the free edge thereof whereby light will pass through said aperture and be reflected by said auxiliary section against the outer face of the main sheet substantially as described.

3. A shade of the character described to be viewed by transmitted light comprising a main translucent sheet having a design thereon, and a semi-transparent auxiliary section 20 secured to said main sheet but spaced therefrom in a part of its area overlying a portion of the design and coordinated with said design to form a part thereof, substantially as described.

4. A shade of the character described to be viewed by transmitted light comprising a main translucent sheet having a design thereon, a translucent auxiliary section secured to said main sheet and having a free edge portion extending outwardly from said main sheet, said main sheet having an aperture 30 behind and along the free edge of said auxiliary section, substantially as described.

In testimony whereof, I have signed my name to this specification this 1st day of March, 1928.

MAX VIVIER.
